PAIR OF GOGGLES

Julius Ellman, Brooklyn, N. Y.

Application June 24, 1957, Serial No. 46,698

Term of patent 14 years

(Cl. D57—1)

Fig. 1 is a front elevational view of a pair of goggles, showing my new design.

Fig. 2 is a top plan view thereof.

Fig. 3 is a cross-sectional view as seen in the direction of the arrows on line 3—3 of Fig. 2.

The rear of the goggles is plain.

I claim:

The ornamental design for a pair of goggles, substantially as shown and described.
